UNITED STATES PATENT OFFICE.

GEORGE SPENCER NEELEY, OF ST. LOUIS, MISSOURI, ASSIGNOR, BY MESNE ASSIGNMENTS, TO GENERAL ELECTRIC COMPANY, A CORPORATION OF NEW YORK.

AUTOMATIC VOLTAGE-REGULATOR.

1,158,001.

Specification of Letters Patent.

Patented Oct. 26, 1915.

Application filed July 1, 1912. Serial No. 707,021.

To all whom it may concern:

Be it known that I, GEORGE SPENCER NEELEY, a citizen of the United States, residing at St. Louis, Missouri, have invented a certain new and useful Improvement in Automatic Voltage-Regulators, of which the following is a full, clear, and exact description, such as will enable others skilled in the art to which it appertains to make and use 10 the same, reference being had to the accompanying drawings, forming part of this specification, in which—

Figure 1 is a diagrammatic view of a system in which my improved regulator is applied directly to the control of the field resistance of the generator. Fig. 2 is a diagrammatic view of my improved regulator showing it utilized in the regulation of the E. M. F. of an independent circuit.

20 This invention relates to improvements in automatic voltage regulators which may be applied to directly regulate the E. M. F. of a generator, or which may be employed to regulate the E. M. F. of some particular 25 circuit, as, for instance, the regulation of the E. M. F. of the lamp circuit in an axle-driven lighting system for railway train lighting.

The novelty of my present invention lies 30 in the provision of features for keeping the regulating resistance, which is of the well known carbon pile variety, in a state of gentle agitation for the purpose of keeping the carbon disks from jamming or packing together in such a manner as to prevent a delicate adjustment of the value of the carbon pile as a regulating resistance.

Another particular advantage gained by 40 my improvement is the overcoming of the objection to the use of the carbon pile as a regulating resistance in railway car lighting systems, namely, that the accumulation of dust between the carbon disks seriously interferes with the sensitive or delicate adjustment of the resistance of the pile to a fine degree.

The principal object of my present invention is to provide simple means for keeping the carbon pile resistance in a continuous 50 state of gentle agitation so that the severe jarring incident to railway travel will not cause the carbon disks forming said pile to settle down into a hard pack. By continuously moving or vibrating the carbon 55 disks of the pile, dust and like foreign sub-

stances will not find permanent lodgment between the surfaces of said disks.

To the above purposes my invention consists in certain features of novelty herein-after more fully described and claimed. 60

Referring to the drawings and particularly to Fig. 1, 1 designates a generator, 2 the field coil thereof, 3, 4 and 5 the external field or voltage controlling circuit in which is connected the two series 6 and 7 of carbon disks. These disks constitute the field regulating resistance, said resistance being regulated by pressure upon the extremities of the disks which constitute a pile. 65

A connecting yoke 8 forms a part of the field circuit between the piles 6 and 7, said yoke being under pressure exerted differentially by a spring 9 and lever 10 in one direction and the magnet core 12 under the influence of the coil or winding 13 in the opposite direction. The winding 13 is constantly under the influence of the E. M. F. of the work circuit 16 and 17. 70

As hereinbefore set forth, one of the advantages of my present invention is to overcome the difficulty of maintaining a fine or close regulation in the application of a carbon pile resistance. This is more particularly noticeable in railway train lighting systems where a great quantity of dust is constantly thrown over the apparatus from the road bed. 75

It is also found that the constant vibration and jarring incident to the movement of a car over the rails causes the carbon disks to pack together, which is another serious objection to the use of carbon piles in train lighting systems. 80

To prevent the disks of the piles 6 and 7 of my improved apparatus from ever remaining in an absolute state of rest for any considerable length of time I employ a relay having a magnet core 14 which is under the influence of the coil or winding 15. This coil 15 is under the influence of the E. M. F. of the work circuit 16 and 17. The magnet core 14 attracts the flexibly mounted armature 18, which is integral with a lever 19. At the free end of this lever 19 is a contact 20 which impinges against a relatively stationary contact 21 for opening and closing circuit 23. A spring 22 is connected to the lever 19 in opposition to the pull exerted by the magnet core 14. The circuit 23 includes a coil 27 opposing the coil 13. 90

100

105

110

The primary object of the relay is to impart a pulsating movement to the yoke 8, and which movement is imparted to the piles of carbon disks 6 and 7 for the purpose of constantly agitating the same to prevent packing and to prevent dust from settling between the surfaces of the disks forming said piles. The pulsating movement is imparted to the yoke 8 in connection with the regulating action of the device as follows:—Assuming the voltage to be on a decrease from normal, when the contacts 20 and 21 are made to impinge by the action of the spring 22, the coil 27 is energized, thereby neutralizing the coil 13. This action causes the spring 9 to retract, thereby exerting an augmented force on the lever 10 and piles 6 and 7. This action reduces the resistance of the piles 6 and 7, which reduction in resistance instantly serves to raise the E. M. F. on the mains 16 and 17, which action, in turn, tends to separate the contacts 20 and 21. This cycle of operations takes place and is maintained with such rapidity that there is no actual visible disturbance in the E. M. F. of the work circuit.

It will be noted that a rising E. M. F. on the work circuit 16 and 17 proportionately increases the strength of the voltage coil 13 on the core 12, which action tends to increase the resistance of the piles 6 and 7. The function of the relay is to supplement this action by a rapid vibratory action obtained by admitting an interrupted opposing flow 35 of current in winding 27 of such duration that a pulsating motion is set up in the yoke 8 supplementary to the regulating movements thereof. This is possible for the reason that the delicately balanced armature 40 18 and lever 19 are so much lighter than the core 12 and lever 10 that they will readily respond to the slighter variations in the E. M. F. of the work circuit occasioned by this slight vibratory action of the piles. 45 This effect produced by the vibrator 19 and its circuit 23 through the medium of coil 27 also operates to make the regulating movements of core 12 regular instead of jerky.

The resistance 25 and winding 26 in shunt thereto serve to give an increasing E. M. F. on an increase of load upon the main circuit. The coil 26 is wound in opposition to the coil 15, so that it will neutralize the same in proportion to the load in the circuit 16, 55 17. This increase in load will, therefore,

operate to increase the neutralizing effect of the coil 27, with the result that the effective pull of spring 9 is increased and the resistance of piles 6 and 7 is diminished.

A closed winding 24 around the core 12 60 of the main regulator serves to eliminate inductive discharging or sparking at the contacts 20 and 21 for the reason that at the moment the circuit 23 is interrupted by the opening of the contacts 20 and 21 a current 65 is momentarily induced in the closed circuit 24, which induced current is of such value as to prevent a sudden drop of the magnetism of the core 12, hence eliminating the possibility of destructive sparking at the 70 contacts 20 and 21.

The device illustrated in Fig. 2 is identical with that illustrated in Fig. 1, but is there shown applied to any circuit other than the field circuit of a generator. Its operation 75 is exactly the same as that described with reference to Fig. 1, to wit, to introduce resistance into the circuit by means of the piles 6 and 7, said resistance being under the control of the coils on cores 12 and 14 in 80 the manner hereinbefore described.

It will be readily understood that minor changes in my improved form of automatic voltage regulator may be made and substituted for that herein shown and described, 85 without departing from the spirit of my invention, the scope of which is set forth in the appended claim.

I claim:

In combination, a circuit to be regulated, 90 a voltage regulator therefor comprising a resistance element in said circuit, means for varying the effect of said resistance, electromagnetic operating means for said resistance varying means, said electromagnetic 95 means comprising opposing coils each responsive to the voltage of the circuit to be regulated and a short-circuited coil, and a relay controlling the energization of one of said opposing coils, said relay being responsive to the voltage of the circuit to be regulated and the current flowing therein.

In testimony whereof I hereunto affix my signature in the presence of two witnesses, this 29th day of June, 1912.

GEORGE SPENCER NEELEY.
